(57) CLAIM

The ornamental design for a hard hat with headset, as shown and described.

DESCRIPTION

FIG. 1 is a top perspective view of the hard hat with headset.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

In some implementations, the headset includes a plurality of cameras, as illustrated in FIGS. 1, 2, 4, and 7.

The broken lines illustrate environmental features that form no part of the claimed design.
